CLAIM

The ornamental design for a reinforcement tab, as shown and described.

DESCRIPTION

FIG. 1 is a perspective view of a reinforcement tab showing my new design;

FIG. 2 is a top plan view thereof; the bottom plan view being a mirror image thereof;

FIG. 3 is a front elevational view thereof; the rear elevational view being a mirror image thereof; and,

FIG. 4 is a left side elevational view thereof; the right side elevational view being a mirror image thereof.

The broken line showing of package is for illustrative purpose only and forms no part of the claimed design.
